(57) **CLAIM**

The ornamental design for a two part reusable dispenser, as shown and described.

DESCRIPTION

FIG. 1 is a front perspective view of a two part reusable dispenser shown in accordance with our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded front perspective view thereof.

The broken lines in the drawings depict portions of the two part reusable dispenser that form no part of the claimed design.

1 Claim, 8 Drawing Sheets
